US0D1022968S

(12) **United States Design Patent** (10) **Patent No.:** **US D1,022,968 S**
(45) **Date of Patent:** **** Apr. 16, 2024**

(54) **HEADSET HOLDER**

(71) Applicant: **RTX A/S**, Nørresundby (DK)

(72) Inventor: **Jens Christian Lindof**, Nørresundby (DK)

(73) Assignee: **RTX A/S**, Norresundby (DK)

(**) Term: **15 Years**

(21) Appl. No.: **29/756,698**

(22) Filed: **Oct. 30, 2020**

(30) **Foreign Application Priority Data**

May 1, 2020 (EM) 007854161

(51) **LOC (14) Cl.** **14-01**

(52) **U.S. Cl.**

USPC **D14/224**; D14/251
